OIL WELL TUBING WRENCH

James S. Taylor, Tulsa, Okla.

Application July 10, 1934, Serial No. 734,547

4 Claims. (Cl. 81—91)

The invention relates to wrenches for rotating oil well tubing sections, and has for its object to provide a device of this character whereby the casing sections may be screwed into or out of 5 couplings connecting the sections, as the tubing is sunk or pulled.

A further object is to provide an oil well tubing wrench comprising a jaw adapted to be received in one side of the tubing, a handle member and 10 a link connection between the handle member and one end of the jaw and provided with means whereby when the handle is moved in one direction said links will cooperate with the adjacent side of the tubing for rolling or forcing the tubing side into the jaw for positively holding the 15 tubing during a screwing or unscrewing operation. Also to provide means whereby upon a reverse movement of the handle said link connection between the handle and jaw will roll the 20 tubing out of the jaw.

A further object is to provide an oil well tubing wrench comprising a jaw segmentally shaped and adapted to arch one side of the tube with a gripping die at the outer end thereof, a handle 25 member adjacent the inner end of the jaw and having a link connection with said jaw end and a link connection with gripping means adjacent its pivotal point to the jaw and cooperating with the periphery of the tube whereby when the 30 handle member is moved in one direction for a tube turning operation the tube will be rolled into gripped position within the jaw and held therein, and when the handle member is moved in the opposite direction said means carried by the 35 link connection will roll the tubing out of its gripped position within the jaw.

With the above and other objects in view the invention resides in the combination and arrangement of parts as hereinafter set forth, shown 40 in the drawing, described and claimed, it being understood that changes in the precise embodiment of the invention may be made within the scope of what is claimed without departing from the spirit of the invention.

45 In the drawing:

Figure 1 is a collective detail perspective view of the portions of the wrench to better illustrate the structure.

Figure 2 is a plan view of the wrench, showing 50 the same in closed position with the upper plate of the link connection removed.

Figure 3 is a plan view of the wrench, showing 55 the same in open position at the starting of the tube rolling and gripping operation and with the upper plate of the link connection removed.

Figure 4 is a plan view of the wrench showing the same in closed position on a tube and the handle in open position in dotted lines and with the upper plate of the link connection removed.

Figure 5 is a plan view of the wrench showing 5 the same on a tube and showing the rolling and gripping plates in their various positions assumed during the tube gripping operation.

Wrenches of this character are relatively large 10 as the tubing sections they grip are necessarily large and of the type used in oil well. In using wrenches of this size in the oil well field three men usually stand around the tubing and each one imparts a pull on the handle for a continuous turning operation. If desired the handle 1 15 may be initially turned where the thread of the tube is stuck by applying a block and tackle to the eye 2 carried by the handle. In wrenches as at present constructed there is not a positive gripping within the jaw, and when there is a 20 frictional gripping it is exceedingly hard to remove the wrench from its gripping position on the tube. The present invention is primarily designed to provide means whereby upon the initial movement of the handle in one direction, the 25 tube will be rolled or forced into gripped position within the segmentally shaped jaw 3 of the wrench, and upon movement of the handle 1 in the opposite direction the gripped tube within the 30 jaw will be rolled from its gripped position within the jaw 3. The jaw 3 is segmentally shaped and has its outer end provided with a die 4 adapted to engage and bite into one side of the 35 outer periphery of the tube section 5.

The inner end of the jaw 3 is pivotally connected at 6 on a shoulder bolt 7 to link plates 8 which are on opposite sides of the jaw, and which plates are provided with gripping teeth or shoulders 9, which, when the links are in open position, as shown at 10 in Figure 5, engage the outer periphery of the tubing 5 opposite the die 4 carried by the jaw, and when the plates 8 are moved towards the tubing 5 from their dotted line positions a in Figure 5, the adjacent side of the tubing is 45 rolled into the jaw 3 on the die 4 as a pivotal point until the plates 8 assume the intermediate full line position b, Figure 5 and the further moving of the plates 8 to the full line position c, Figure 5 will force the tubing into gripped relation within the jaw 3, thereby positively gripping the tubing and positively holding the wrench on the tube. When it is desired to remove the wrench from the tubing a reverse movement of the handle 1 in the direction of the arrow d will cause the gripping 50 55

teeth 9 of the plate to roll the tubing out of its gripped position within the segmental jaw 3.

The handle member 1 at its inner end is pivotally connected on shouldered bolts 11 between the gripping plates 8 and is provided with an arm 12 which cooperates with an integral arm 13 carried by the inner end of the segmentally shaped jaw 3 for positively forcing the gripping and rolling plates 8 towards the tube 5 during a gripping operation. Handle member 1 is normally forced towards closed position by means of a coiled spring 14 surrounding the shaft 15 which is pivotally connected at 16 to the gripping plates 8 and is slidably mounted in the chamber 17 in the extension 18 in one side of the handle.

When it is desired to remove the wrench and the handle is moved in the direction of the arrow *d*, the spring 14 and shaft 15 will form a stop for the handle, and this will cause a pivotal action of the gripping plates 8 on the pivotal point 6, and during this movement the gripping teeth 9 of the plates 8, which engage the side of the tube 5 opposite the die 4, will roll the tube out of its gripped position within the jaw 3. It is obvious that the gripping teeth 9 of the plates may be in the form of dies the same as the die 4 if desired, and that the arcuate portions 19 of the gripping plates and 20 of the jaw 3 are on arc corresponding to the outer diameter of the tube, hence it will be seen there is a positive gripping and holding of the tube at all times during a tube rotating operation. Jaw 3 is provided with a handle member 21 adapted to be gripped while manipulating the wrench for instance when placing the same in position or removing the same.

From the above it will be seen that a wrench is provided for rotating oil well tube sections during a screwing or unscrewing operation, that the wrench is positively gripped on the tube with the tube gripped in the segmentally shaped jaw and that upon initial movement of the handle in one direction the tube is rolled into gripped position within the jaw for positively attaching the wrench and holding the tube, and upon movement of handle in the opposite direction the tube is rolled out of gripped position within the segmentally shaped jaw.

The invention having been set forth what is claimed as new and useful is:

50 1. A tubing wrench comprising a semicircular shaped jaw adapted to arch one side of a tube, the outer end of said jaw having a tube gripping member, a handle member adjacent the inner end

of the jaw, a link connection between the handle member and the inner end of the jaw and forced into engagement with the tube upon movement of the handle member in one direction, said link connection having tube engaging means adjacent its pivotal connection to the jaw and cooperating with the periphery of the tube whereby upon movement of the handle in one direction a tube will be rolled into the segmentally shaped jaw and gripped therein and upon movement in an opposite direction a tube will be rolled from its gripped position within the jaw.

2. A tube wrench comprising a segmentally shaped jaw adapted to arch one side of a tube, a handle member, a link connection between the handle member and the inner end of the jaw, and means carried by the link connection adjacent its pivotal connection to the jaw and cooperating with the periphery of a tube whereby one side of a tube will be rolled into and out of gripped position within the jaw at the link side of the jaw upon movement of the handle in one direction or the other.

3. A wrench comprising a segmentally shaped jaw adapted to arch one side of a tube, means carried by the outer end of said jaw for biting into one side of the tube, gripping plates pivotally connected to the other end of said jaw at opposite sides thereof, a handle member pivoted between the plates, an arm carried by the handle member adjacent its pivotal point and extending towards the inner end of the jaw, an arm carried by the inner end of the jaw and extending towards the handle member and to the outer side of the arm carried by the handle member and in the path thereof, and tube engaging teeth carried by the plates adjacent their pivotal connection to the jaw and adapted to engage the outer periphery of a tube and roll the tube into the jaw.

4. The combination with a tube wrench of the character described and comprising a segmentally shaped jaw arching one side of a tube in engagement with the periphery thereof, a pivoted handle member, a link connection between the jaw and the handle member, of means carried by the link connection adjacent its pivotal connection to the jaw and cooperating with the periphery of the tube at one side thereof for rolling said tube into and out of gripped position within the jaw.

JAMES S. TAYLOR.
